Attorney, Agent, or Firm—Whyte Hirschboeck Dudek

[57] CLAIM

The ornamental design for a truck body—side sections, as shown and described.

DESCRIPTION

FIG. 1 is a front perspective view of a truck body—side sections showing our new design;

FIG. 2 is a back perspective view; and,

FIG. 3 is a side elevation, with the opposite side being a mirror image.

The broken lines shown in all figures are for illustrative purposes only and form no part of the claimed design.
